UNITED STATES PATENT OFFICE.

WILLIAM F. TAYLOR, OF MINNEAPOLIS, MINNESOTA.

VENDING-MACHINE.

1,306,201.

Specification of Letters Patent. Patented June 10, 1919.

Application filed April 27, 1916. Serial No. 93,831.

To all whom it may concern:

Be it known that I, WILLIAM F. TAYLOR, a citizen of the United States, residing at Minneapolis, in the county of Hennepin and State of Minnesota, have invented certain new and useful Improvements in Vending-Machines; and I do hereby declare the following to be a full, clear, and exact description of the invention, such as will enable others skilled in the art to which it appertains to make and use the same:

My invention relates to coin-controlled vending machines, and generally stated, has for its object to simplify the construction and improve the operation thereof.

Particularly, the invention is directed to improved mechanism which makes practicable the use of a single coin mechanism to control the delivery of articles from any one of a multiplicity or group of magazines; but the invention also involves other important features capable of use either in multiple-magazine machines, or in single magazine machines.

In the arrangement of the multiple-magazine machine, the magazines which may contain the same or very different articles which are to be sold at the same price, are preferably placed in a row and the articles are discharged therefrom by independently operable ejectors, preferably in the form of slides. Normally, all of the slides for the particular group of magazines, are secured in positions to prevent the discharge or escape of articles from the respective magazines, by means of a so-called limiting lock, which, when released, will permit any one of the slides, but one slide only, to be moved from normal position into position to cause or to permit the discharge of one article from the coöperating magazine. This limiting lock includes a so-called tripping lever that normally coöperates with the other lock elements to hold all of the slides in normal position, as above stated; and this tripping lever has a coin receiving pocket, which, when a coin of the proper denomination is deposited therein, will move said lever into a lock-releasing position.

The coin deposited in the pocket of the releasing lever, after one of the released slides has been operated, will be ejected and dropped through a chute to an intercepting device which temporarily holds the coin in front of a sight opening for the purpose of

inspection, and, subsequently, drops the same into a suitable coin receptacle.

With the above general statements in mind, the following detailed description will be readily understood.

In the accompanying drawings which illustrate the invention, like characters indicate like parts throughout the several views.

Referring to the drawings:

Figure 1 is a view chiefly in vertical section, but with some parts in side elevation, showing the improved multiple-magazine machine;

Fig. 2 is a horizontal section taken on the line $x^2 x^2$ of Fig. 1;

Fig. 3 is a detail view in plan, showing parts found in the vicinity of the line marked $x^3 x^3$ of Fig. 1;

Fig. 4 is a vertical section on the line x^4 x^4 of Fig. 3;

Fig. 5 is a front elevation of the machine;

Fig. 6 is a vertical section taken on the line $x^6 x^6$ of Fig. 1;

Fig. 7 is a section taken approximately on the same line as Fig. 1, but with some parts broken away, and with the parts shown on a larger scale than in Fig. 1;

Fig. 8 is a view corresponding in line of its section to Fig. 2, but with the parts on a larger scale and with some parts broken away;

Fig. 9 is a vertical section taken approximately on the line $x^8 x^8$ of Fig. 7, some parts broken away;

Fig. 10 is a section taken approximately on the line $x^{10} x^{10}$ of Fig. 9;

Fig. 11 is a fragmentary view in section taken approximately on the same line as Fig. 9, but with some parts broken away;

Fig. 12 is a horizontal section on the irregular line $x^{12} x^{12}$ of Fig. 9; and

Fig. 13 is a perspective view showing a machine made up of a multiplicity of compartments having a common case.

Referring to the construction illustrated in Figs. 1 to 12, inclusive, the numeral 1 indicates a rectangular case or cabinet shown as provided with a displaceable cover 2 and with a horizontal partition 3. The magazines 4 for containing the articles to be dispensed, are vertically positioned in rows aligned from front to rear of the case, and are provided with raised bottoms 5 by means of which they are rigidly secured to the horizontal partitions 3. Here it is important to

note that the said raised bottoms 5, in a direction from rear to front of the case, are made progressively higher. The above statement is true in respect to all but the rearmost 5 magazine, which, as shown, is directly secured to the partitions 3. In front of each magazine, the partition 3 is provided with a parcel discharge passage 6 that directly overlies an oblique discharge chute 7, the 10 lower end of which extends through the front wall of the case close to the bottom thereof and in position where a discharged parcel may be reached by the fingers of the operator.

15 As shown, there are four magazines in the machine illustrated, and hence, for coöperation therewith, I provide four spring retracted parcel ejectors or ejecting slides 8, the front ends of which work through guide 20 slots in the front place of the case 1 and terminate in suitable heads, adapted to be engaged by the fingers of the operator. The said slides 8 are located in a vertical row, one over the other, and in a direction from 25 top to bottom, they are progressively longer and longer, so that the upper slide projects to the rear of the front magazine, the second slide from the top to the rear of the second magazine from the front, the third slide from the front and the bottom slide to the 30 rear of the rearmost magazine. The said slides coöperate with the said magazines in the order just described, and, under forward movements, will eject articles from the coöperating magazine and discharge the same 35 through the coöperating passages 6. The arrangement of the slides for accomplishing this result may be varied, but, as shown, the rear portion of each such slide is in form of 40 a rectangular yoke 8^a, which, at the rear, terminates in angular lugs 8^b. These lugs 8^b, when the slide is moved forward, positively carry the bottom-most article from the magazine to the discharge passage 6 and 45 temporarily hold up the other articles in the magazine until the slide has been restored to normal position. The slides 8 are retracted by springs 8^c, (see Fig. 7).

By reference particularly to Figs. 7 and 8, 50 it will be noted that the front portions of the slide yokes 8^a and the rear portions of the slide proper 8, work through a rectangular guide frame 9 secured on the partition 3. This guide frame 9 cooperates with the 55 transverse front bar of the yokes 8^a to limit the forward and rearward movements of the ejecting slides.

The slide limiting lock mechanism, as 60 preferably constructed, involves a plurality or stack of metallic balls or similar loosely associated elements 10 that are contained in the upright metallic tube 11 shown as rigidly secured in its lower end to the partition 3, and also to any other convenient support, 65 not shown. The upper end of the tube 11 is

closed against the escape of the upper ball 10, but has a narrow slit through which works a narrow stop lug or blade 12 of a so-called lock-releasing lever 13 that is intermediate pivoted at 14, to a bifurcated upper 70 end extension 15 of the tube 11. At one end, this lever 13 has an upwardly flaring coin receiving pocket 16 that is open at its bottom and at one side. The upwardly flaring or downwardly converging edge walls of the 75 pocket 16 are so spaced at their lower extremities that they will catch and hold a coin of the proper denomination, but will let pass any smaller coin. The other end of the lever 13 is so weighted that it will hold the lever 80 13 with its coin pocket raised, as shown by full lines in Fig. 9, but will be rocked into the position indicated by dotted lines in Fig. 9 and by full lines in Fig. 11, whenever a coin of the proper denomination, to-wit, 85 proper size and weight, is caught and temporarily held in the pocket 16.

When the lock-releasing lever 13 is in its normal position just stated, its lock lug 12 will engage or stand close to the upper ball 90 10 and will prevent separation.

In each ejector slide 8 (see particularly Figs. 9, 11 and 12) I provide a laterally projecting so-called lock blade 17, that is of a thickness which will approximately 95 take up the play permitted between the balls 10, when the lock lug 12 of the lever 13 is retracted and the upper ball is then capable of being moved against the upper end of the tube 11. The tube 11 is provided with 100 slots 11^a that permit the blades 17 to engage with the balls 10.

With this arrangement, th refore, normally, and when the lever 13 is in the position shown by full lines in Fig. 9, no one 105 of the ejector slides can be drawn outward or operated, because there is then not sufficient play between the balls 10 to permit one of the blades 17 to be forced between any two balls. When, however, the lever 13 is 110 in its releasing position shown in Fig. 11, any one of the slides may be drawn outward, or into a parcel ejecting position, thereby carrying its blade 17 between the adjacent balls 10, as shown in Fig. 11, but 115 when this is done, all of the other ejector slides are locked in their normal or inoperative positions, because there is then not sufficient play between the balls to permit a second blade 17 to be forced between them. 120

The coin may be delivered to the receiving pocket of the releasing lever 13 in any suitable way, but, as shown, this is accomplished as follows, attention being called particularly to Figs. 1, 3, 4, 9 and 10, where- 125 in the numeral 18 indicates a coin depositing slide mounted in a guide housing 19 and provided with a coin receiving perforation 20 that is adapted to carry the coin from the casing 19 into the upper extremity of 130

an inclined coin delivery chute 21, the lower end of which terminates in position to deliver the coin directly into the flaring pocket 16 of the lock releasing lever 13.

5 When the coin is deposited into the said pocket 16, it is prevented from falling laterally out of the open side thereof, by means of a retaining head 22 carried by an arm 23 on the upper end of a vertical rock shaft 24, which rock shaft, as shown, is journaled at its upper end in a bearing 25 on the guide frame 9, and at its lower end, is journaled in a suitable bearing on the partition 3. This rock shaft, at its upper end, is also 10 provided with a coin ejecting finger 26, the end of which is spaced from the retaining head 22 and normally stands on the opposite side of the coin-receiving pocket 16. The rock shaft 24, also, is provided with a plurality of projecting trip arms 27, one for each ejecting slide. The front ends of these trip fingers 27 normally stand as shown in Fig. 12, projecting through perforations in the front portion of the bearing yoke 9, and 15 in position to be engaged by the front portion of the yoke 8^a of the corresponding ejector slide 8. Normally, the rock shaft 24 is held with the coin-retaining head 22 and trip arm 27 in the position indicated by full 20 lines in Figs. 10 and 12, by means of a coiled spring 28 shown as anchored to the bearing yoke 9 and the arm 29 on said rock shaft.

Whenever one of the slides 8 is drawn out, 25 as above described, the front portion of its yoke 8^a will engage the coöperating trip arm 27 of the rock shaft 24 and thereby move the coin retaining head 22 away from the coin, and the coin ejecting arm 26 against the coin, and thereby force the said coin 30 out of the pocket 16. The coin thus ejected from the pocket of the lock releasing lever 13 will drop into the flaring upper end of a second coin chute 30. The inclined lower 35 end of this chute 30 delivers the coin to a scoop-like coin interceptor 31 that is pivoted at 32 to a bearing on the partition 3, and is provided with an upwardly extended arm 33 adapted to be engaged by pins 34 on the several slides 8. Normally, or when all of 40 the slides are in normal position, this coin interceptor is yieldingly held by gravity, or otherwise, in the position shown in Fig. 1, wherein it holds a previously deposited coin 45 y in front of a sight opening 35 formed in the front plate of the case 1. When any one of the ejector slides 8 is drawn out, the coin interceptor will be moved into the position indicated by full lines in Fig. 7, and will 50 then drop the coin y into a coin receptacle shown as in the form of a drawer 36 slidably mounted in the casing 1 and normally locked. Here it should be noted that when an ejecting slide is drawn out and the coin 55 interceptor rocked, as shown by full lines

in Fig. 7, its back flange is projected upward through a slot 30^a in the chute 30, so that it will then stop a coin delivered into said chute by an action resulting from the movement of the said operated slide 8. 70 When the said ejector slide is again restored to normal position, the coin interceptor will be moved back to the position shown in Fig. 1 and will catch and temporarily hold the last deposited coin, as already indicated. 75

As already stated, the parcels contained in the several magazines should be of the same value, but may be either identically the same parcels or parcels of very different character. The said parcels, in Figs. 7 and 80 8, are indicated at y¹.

Fig. 13 shows a machine made up of three sections, such as above described, but each having a different number of magazines, and each section, of course, having its own coin 85 mechanism. In this illustration, the casing is indicated by the character 1^a, its cover by 2^a, the several delivery chutes at 7^a, the several coin drawers or receptacles at 36^a and the several ejector slides a⁸. Figs. 5 and 13 90 diagrammatically show label holders 37 aligned with the heads of the ejector slides a⁸, and which may be marked to indicate the kind of parcels delivered by operation of the particular slide. 95

What I claim is:

1. In a vending machine, the combination with a plurality of magazines, of a plurality of parcel ejectors, one for each magazine, a limiting lock mechanism having a multiplicity of separable elements normally locking all of said ejectors, and a releasing lever normally holding the separable elements of said lock mechanism against separation, but movable into a position to permit a limited separation of said lock elements, to thereby permit any one of said ejectors to be operated. 100

2. In a vending machine, the combination with a plurality of magazines, of a plurality of ejector slides, one for each magazine, a limiting lock mechanism comprising a multiplicity of separable elements and a container therefor, said slides having blades arranged to pass between the said separable lock elements when the latter are free to separate within said container, and a releasing lever normally holding said lock elements against separation, so that no blade can be passed between members thereof, 110 thereby normally locking all of said ejector slides, the said lever being movable to release said lock elements, the said container then permitting a separation thereof which will permit the blade of but one slide to be 115 moved therebetween at any one time. 120

3. In a vending machine, the combination with a plurality of magazines, of a plurality of parcel ejectors, one for each magazine, a limiting lock mechanism having a multiplicity 130

ity of separable elements normally locking all of said ejectors, and a releasing lever normally holding the separable elements of said lock mechanism against separation, but 5 movable into a position to permit a limited separation of said lock elements, to thereby permit any one of said ejectors to be operated, said lever having a coin-receiving pocket, and means for ejecting the coin from

said pocket whenever one of said parcel 10 ejectors is operated.

In testimony whereof I affix my signature in presence of two witnesses.

WILLIAM F. TAYLOR.
